Patented Apr. 7, 1925.

UNITED STATES PATENT OFFICE.

JAMES W. IVORY, OF PHILADELPHIA, PENNSYLVANIA,

RUBBER-DAM CLAMP.

Application filed May 14, 1924, Serial No. 713,130.

To all whom it may concern:

Be it known that I, JAMES W. IVORY, a citizen of the United States, residing Philadelphia, in the county of Philadelphia, State of Pennsylvania, have invented a new and useful Rubber-Dam Clamp, of which the following is a specification.

My invention relates to clamping devices, and more particularly to rubber dam clamps, for use in dental and like operations, which are provided with means for positively securing the rubber dam to the clamp, while the latter is adjusted to the tooth, so that the dam will be prevented from unintended slipping from the clamp when adjusted thereon, but will retain the desired position until it is removed from the clamp.

It has been found that in clamps of this character, in the prior art, there has been a tendency of the rubber dam to slip upwardly from its position of placement on the clamp, and I have so constructed my present clamp to overcome this difficulty. One of the objects of my invention is to provide means in a clamp of this character which will permit it to be readily adjustable to and removed from a tooth, and which will provide means for securely and positively retaining the dam in the desired position and adjusting it in relation to the tooth during the operation and during the adjustment of the clamp to the tooth.

My invention consists in the particular combination, or organization and arrangement of parts hereinafter described in this specification and more particularly pointed out in the appended claims.

For the purpose of illustrating my invention I have shown in the accompanying drawing forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Figure 1 is a perspective view of a clamp embodying my invention.

Figure 2 is a perspective view of a clamp embodying a modified form of my invention.

Figure 3 is a perspective view of a clamp

embodimenting another modified form of my invention.

Figure 4 is a partial sectional view on line 4—4, Figure 2, showing the embodiment of one form of my invention.

Figure 5 is a partial sectional view on line 5—5, of Figure 1, showing the embodiment of another form of my invention.

Figure 6 is a partial sectional view, on line 6—6, of Figure 3, showing the embodiment of another form of my invention.

Figure 7 is a perspective view of another modified form of my invention.

Figure 8 is a perspective view of another modified form of my invention, similar to the embodiment in Figure 1.

Figure 9 is a perspective view of another modified form of my invention, showing means to more positively retain the rubber dam in position on the lateral flanges in addition to the embodiment shown in Figure 2.

Figure 10 is a perspective view of another modified form of my invention, similar to that shown in Figure 3 illustrating the restraining arms shortened.

Figure 11 is a perspective view of another modified form of my invention showing the lateral restraining flanges reduced in curvature and length.

Figure 12 is an embodiment of my invention having a rubber dam applied thereto.

Referring to the drawings:

Similar numerals of reference indicate corresponding parts.

1 is a rubber dam clamp, formed of the jaws 2, the connecting bow spring 3 the lateral flanges 4 on the outer side of the jaws 2, and the apertures 5, for the engagement therewith of forceps, to spread apart the jaws 2 of the clamp, which instruments are well known in the art.

In the outer side edges of the jaws 2 and flanges 4, near the projecting arms 6, which are located at the outer terminals of the jaws 2, are the recesses 7, the walls of which form the shoulders 8.

In the outer side edges of the jaws 2 and the flanges adjacent the bow 3, are the recesses 9 (Figure 7), the walls of which form the shoulder 10. The respective recesses 9, extend substantially convergently radially inwardly, and are preferably formed rounded at their inner ends.

In the embodiment of my invention here-

with presented, special attention is directed to the formation, curvature and shape of the lateral flanges 4, the function of which is to carry and retain in its desired operative position of placement, the rubber dam (shown in Figure 12 but which is no part of my invention). It is desired to provide these means of such shape and character, that the rubber dam will be firmly held from slipping, will be retained, when desired in the proper position in relation to the clamp and the tooth around which it is placed and will also prevent unnecessary tearing and cutting of the rubber dam by rough or sharp edges of teeth with which it may come in contact.

I accomplish this by providing my improved clamp with lateral flanges 4 having a particular form, construction and curvature and by positioning the projecting arms 6 in suitable relation thereto.

As will be seen from an inspection of the various figures of the drawings, the flanges 4 extend from either side of the jaws 2, dip toward the gum line and diverge angularly from each other. These arms are concaved or hooked on their outer face or outline, while on their inner face or outline they terminate with a convex curve over and away from the gum tissue. This formation of the flanges with the bulging curves, provides an efficient, simple and positive anchorage for the rubber dam when applied and adjusted thereon and with the projecting arms 6, firmly holds the dam in the desired position, while at the same time permitting its ready removal when desired.

The flange portion 4 of the faces 2 are provided with elongated apertures or slots 11, for the application therein of an instrument, when it is desired to strip the dam from the clamp.

Although the preferred form of embodiment of my invention, having the curved shape above described, is shown in Figure 1, and Figure 5, yet I have illustrated in other figures of the drawings some modification thereof.

In Figure 2 and Figure 4 is shown a modification, having a flange with a top curved portion 12, a substantially straight, angularly disposed, intermediate portion 13, which terminates in an upwardly deflected outer terminal portion or lip 14, laterally extending therefrom. When the dam is applied to this form of clamp it is carried on the intermediate portion 13 and is prevented from accidental downward displacement by the terminal portion 14, while the arms 6 and the curved top portion 12 prevent the dam from undesired upward displacement.

In Figure 3 and Figure 6 is shown another modification, in which the flanges 4 dip downwardly in a curved formation, from the plane of the body portion of the jaws 2 and diverge laterally from each

other, terminating in an upwardly curved portion having its outer face or outline concaved as at 15. When the rubber dam is applied to this modified form of clamp, it is held against downward displacement by the curved portion 15 of the flanges and against upward displacement by the shoulder 16 and the arms 6.

In Figure 7 is shown another modification, in which the flanges 4 are formed with a slightly projecting tongue 17, adjacent the arms 6 and the ends of the jaws 2 opposite therefrom are cut away adjacent the bow spring 3, so as to form projecting portions or stops 18. These tongues 17 and stops 18, engage the rubber dam, when it is applied to the flanges 4, and thereby with the arms 6, hold it against any tending to ride upwardly on the flanges 4 and be displaced from its desired operative position.

In Figure 8 is shown another modification, in which the curvature of the upper part of the flange 4 is substantially that shown in Figure 1 and Figure 5, it being above the plane of the body portion of the jaws 2, while the lower part of the flange 4 is substantially that shown in Figure 3 and Figure 6.

In Figure 9 is shown another modification, in which the shape of the flange 4 is substantially that shown in Figure 2 and Figure 4, having in addition tongues 19, formed on either end of each flange. These tongues 19 are adapted to engage the rubber dam when it is applied to the flange 4, and with the arms 6, thereby restrain it against any undesired upward displacement from its operative position on the clamp.

In Figure 10 is shown another modification, substantially similar to that shown in Figure 1 and Figure 5, but having the arms 6 of somewhat reduced length.

In Figure 11 is shown another modification, substantially similar to that shown in Figure 1 and Figure 5, but having the flange 4 of somewhat reduced length and its angle of disposition, relative to the jaws 2, more acute than shown in the figures herein above referred to.

The operation of my device is as follows:

An opening is made in a sheet of rubber dam. This opening is distended and the flanges 4 of the clamp are inserted thereon, with the arms 6 positioned above the rubber dam, as shown in Figure 12 of the drawings.

Suitable forceps are then inserted in the openings 5 and the jaws 2 of the clamp are spread apart, carrying with them the rubber dam mounted on the flanges 4. The jaws may be placed in position over a tooth and when released from the forceps will engage the body of the tooth and by the pressure exerted by the bow spring 3, the clamp and rubber dam carried thereon, will be se-

surely held in the desired position. The clamp may be removed from the tooth by the reinsertion of the forceps into the openings 5 and spreading the jaws 2 apart, until they 5 are out of engagement with the tooth body. It may then be readily removed.

Because I have formed the face of the flange 4 in a concave curve, in one portion, and a convex curve in an adjacent portion, 10 the rubber dam, when mounted thereon, is securely held taut at its extreme edge. And further owing to its elasticity it will so stretch, when the clamp is spread, that it will permit this extreme thin edge to more 15 readily pass between contiguous teeth, while at the same time, because of the concaved and convexed form of the flange 4, the rubber dam is prevented from sliding or being otherwise accidentally displaced from the 20 desired position on the flanges 4.

From the above description, it will be obvious how the projecting tongues 17 and stops 18 in the embodiment of my device shown in Figure 7, and the tongues 19 in the 25 embodiment shown in Figure 9, engage the rubber dam, when it is mounted upon the flanges 4, substantially as shown in Figure 12, and thereby more positively hold it against upward movement on the flanges 4. 30 From the foregoing description, it will be seen that I have provided a simple and efficient device, which overcomes the defects existing in devices of this character in the prior art.

While I have thus specifically described my invention, I do not wish to be limited thereby, except as the state of the art and the appended claims may require, for it is 35 obvious that various changes may be made 40 in the construction and arrangement of parts thereof, without departing from the spirit and scope of my invention.

Having thus described my invention, what I claim as new and desire to secure by Letters Patent, is:

1. In a rubber dam clamp, tooth engaging and clamping jaws, connected by a bow spring, each jaw having dam-holding means

of a curvilinear formation, convex at its inner end, and having an outer upwardly deflected terminal. 50

2. In a rubber dam clamp, tooth engaging and clamping jaws, connected by a bow spring, each jaw having dam-holding means 55 of a curvilinear formation, concave at its outer free end and convex at its opposite end.

3. In a rubber dam clamp, tooth engaging and clamping jaws, connected by a bow spring, each having dam-holding means 60 of a curvilinear formation formed integral therewith, concave on the outer face of its outer free end and convex on the outer surface of its upper end.

4. In a rubber dam clamp, tooth engaging and clamping jaws, connected by a bow spring, each jaw having laterally disposed 65 dam-holding means of a curvilinear formation, concave on the outer face of its outer lower end and convex on the outer face of 70 its opposite end.

5. In a rubber dam clamp, tooth engaging and clamping jaws, connected by a bow spring, each jaw having an angularly depending, laterally disposed, dam-holding 75 rib of a curvilinear formation, concave on the outer face of its lower end and convex on the outer face of its upper end.

6. In a rubber dam clamp, tooth engaging and clamping jaws, connected by a bow 80 spring, each jaw having a laterally disposed dam-holding rib of a curvilinear formation, concave at its lower end and convex at its upper end and a laterally disposed arm adjacent one extremity of said dam-holding 85 means.

7. In a rubber dam clamp, tooth engaging and clamping jaws, connected by a bow spring, each jaw having laterally disposed 90 dam-holding rib, convex at its upper inner portion and having its lower outer terminal deflected upwardly and dam engaging tongues projecting from the end walls of said convex portions.

JAMES W. IVORY.
